[57] CLAIM

The ornamental design for a combined writing board and holder, as shown and described.

DESCRIPTION

FIG. 1 is a perspective view of a combined writing board and holder showing our new design;

FIG. 2 is a top plan view thereof;

FIG. 3 is a side elevational view thereof;

FIG. 4 is an end elevational view thereof;

FIG. 5 is an end elevational view of the end opposite that shown in FIG. 4; and

FIG. 6 is a bottom plan view thereof.

FIG. 1

FIG. 2

FIG. 3

FIG. 4

FIG. 5

FIG. 6
